Application October 12, 1933, Serial No. 693,251

14 Claims. (Cl. 250—20)

The present invention relates to systems for and a method of transferring radio frequency currents and the remote control of electrical devices with the use of residence lighting conductors and, more particularly, to a method of and system for the remote control of the amplifier and associated speaker unit of a radio receiver wherein residence lighting conductors are used as the sole connection between the tuner unit and the amplifier and associated speaker unit.

General objects of the invention are the provisions of systems for and methods of transferring the radio frequency currents and control currents for remote control devices with the use of residence lighting conductors which are efficient in operation and make possible convenient location of the units thereof in any desired position convenient to an outlet in the residence lighting circuits on residence premises.

A more specific object of the invention is the provision of a method whereby radio frequency currents may be transferred from one device to another by units of low impedance coupling to connect the devices to the residence lighting conductors.

Another object of the invention is the provision of a system wherein the tuner unit and the amplifier and associated speaker unit of a radio receiver may be located at remote points with the sole connections therebetween comprising the residence lighting conductors to which each of the units is coupled by low impedance.

A further object of the invention is the provision of a system whereby switches and other electrical devices may be remotely controlled with the use of the residence lighting conductors by the utilization of a unit adapted to superpose upon the alternating current of the residence lighting conductors a control current component, such as, an oscillatory current of a frequency different from that of the frequency of the current in the residence lighting conductors, or a direct current component, to which another unit will respond.

A still further object of the invention is the provision of such a device wherein the tuner unit and the amplifier and associated speaker unit of a radio receiver remotely located are connected together by coupling each of said units with low impedance coupling to residence lighting conductors and the amplifier circuit switch is operated by a device responsive to a control current component superposed on the current of the residence lighting conductors by a unit associated with the remotely located tuner unit.

Other objects of the invention will in part be obvious and will in part appear hereinafter.

The invention accordingly comprises the several steps and the relation of one or more of such steps with respect to each of the others, and

the apparatus embodying features of construction, combination of elements and arrangement of parts which are adapted to effect such steps, all as exemplified in the following detailed disclosure, and the scope of the invention of which will be indicated in the claims.

For a fuller understanding of the nature and objects of the invention reference should be had to the following detailed description taken in connection with the accompanying drawings, in which:

Fig. 1 is a simplified schematic view of the tuner unit and amplifier and speaker unit of a radio receiver remotely located, utilizing the principle of the present invention;

Fig. 2 is a diagrammatic view of the circuit of a radio receiver utilizing principles of the present invention;

Fig. 3 is a diagrammatic view of the circuit of a selective energizer utilized in the present invention;

Fig. 4 is a diagrammatic view of the circuit of another type of selective energizer;

Fig. 5 is a diagrammatic view of the circuit of a selective responder utilized in the present invention;

Fig. 6 is a diagrammatic view of the circuit of another type of selective responder; and

Fig. 7 is a diagrammatic view of the circuit of an additional type of selective responder which may be utilized with the type of selective energizer depicted in Fig. 2.

The present invention involves systems of transferring radio frequency current with the use of residence lighting conductors, for example, the transfer of such currents from the tuner unit of a radio receiver to the amplifier and speaker unit thereof, and to a method for effecting such transfer. This transfer is obtained by connecting the units to the residence lighting conductor through low impedance coupling. In addition, the invention involves the utilization of the residence lighting conductors for remotely controlling devices such as electrical switches, for example, for operating the circuit switch of the amplifier and associated speaker unit of a radio receiver from a remotely located tuner unit. According to the present invention, this involves the use of a selective energizer for superposing on the residence lighting conductors a control current adapted to operate a remotely located selective responder.

Referring to the drawings like numerals denote like parts throughout. The tuner unit of a radio receiver is designated by the numeral 10 which in Fig. 1 is shown connected to the usual aerial 11 and ground connection 12. To the plate 13 of a tube, preferably an intermediate frequency amplifier tube, is shown connected the primary 14 of an intermediate frequency step down cou-

pling transformer. The secondary 15 of the coupling transformer is shown capacitance coupled, preferably by condensers 16 and 17 in wires 18 and 19, to the terminals of a plug 20 of the usual type adapted to be received in an outlet 21 in the residence lighting circuit depicted at 22. In between the capacitance coupling and the plug 20 a selective energizer 23 adapted to supply to the residence lighting conductors a control current is connected by wires 24 and 25 to wires 18 and 19.

The amplifier and speaker unit 26 of the radio receiver is provided with a tube, preferably an intermediate frequency amplifier tube, the grid 27 of which is connected to the secondary 28 of an intermediate frequency step up coupling transformer. The primary 29 is capacitance coupled, preferably through condensers 30 and 31 in wires 32 and 33 to the plug 20' adapted to be received in an outlet 21' in the residence lighting circuit. Between the capacitance coupling and the plug 20' is connected, by wires 34 and 35, a selective responder unit 36 adapted to be operated by the control current generated by the selective energizer 23 to close the circuit switch 37 of the amplifier and associated speaker unit 26.

In Fig. 2 is shown the circuit of a radio receiver and associated apparatus such as that depicted in Fig. 1 utilizing the principles of the present invention. The antenna 11 is connected to an antenna coupling transformer 38 having one side of the secondary thereof connected to the control grid 39 of a first detector vacuum tube 40. Across the secondary of the coupling transformer 38 is connected a variable tuning condenser 41, grounded through a wire 42 to the wire 19 connected to one of the residence lighting conductors 22. The tube 40 is of the screen grid type having an indirectly heated cathode 43, a screen grid 44 and a plate 45. The screen grid 44 is connected through a wire 46 to a voltage divider 47 which is bridged across between wires 42 and 48. The plate 45 is connected to one end of the primary of an intermediate frequency transformer 49. The other end of the primary is connected to the wire 48.

In accordance with principles of super-heterodyne amplification an oscillator tube 50 has its plate 51 connected to the wire 48 through a portion of a transformer 52 and its control grid 53 connected through a grid coupling condenser 54 to one end of the primary of the transformer 52. The other end of the primary is connected to the indirectly heated cathode 55 of the oscillator tube 50. An oscillator grid leak 56 is connected across between the grid 53 and cathode 55 and a variable tuning condenser 57 is connected across the primary of the transformer 52. A wire 58 connected to the wire 42 grounds the oscillating circuit. The frequency of the current supplied by the oscillator 51 and its associated circuit is fed into the cathode 43 of the first detector 40 through a coupling coil 59 of the transformer 52 and the bias resistor 60 with the latter bridged by a by-pass condenser 61.

An intermediate frequency amplifier tube 62 has its control grid 63 connected to one end of the secondary of the intermediate frequency transformer 49 and the cathode 64 connected through a bias resistor 65, to the other end of the secondary. The resistor 65 is by-passed by condenser 66. This grid circuit is grounded by a wire 67 to the wire 42. The screen grid 68 of the amplifier tube 62 is connected to the wire 46 which serves as a common conductor to the

voltage divider 47. The plate 13 of the amplifier 62 is connected to one end of the primary 14 of the intermediate frequency step down coupling transformer. The other end of the primary 14 is connected to the wire 48.

Across the secondary 15 of the intermediate frequency coupling transformer is connected the resistance element of a volume control 69. Sliding contact of the volume control 69 is connected through the condenser 16, wire 18, and a switch 10 70 to one of the residence lighting conductors 22. One side of the secondary 15 of the intermediate frequency coupling transformer is connected through the condenser 17 and wire 19 to the other residence lighting conductor 22.

A ballast resistor 71 is connected to the supply wire 18. The heater elements of each of the vacuum tubes 72, 62, 50 and 40 are connected in series with each other and with the ballast resistor 71. This filament supply circuit is completed by the wire 42 forming a connection between one end of the filament of the tube 40 and the supply wire 19.

The plate voltage is supplied by a rectifier tube 72 having a plate 73, connected through the wire 18 and the switch 70 to one of the residence lighting conductors 22, and an indirectly heated cathode 74, connected through the choke coil 75 to the wire 48 to which the plates of the previously described vacuum tubes are connected. The plate voltage supply circuit is completed through the respective vacuum tubes, the cathodes thereof being connected to the wire 42, the latter being connected to the other residence lighting conductor 22 through the wire 19. Condensers 76 and 77 are bridged across from the wire 78 connected to wire 18 to the indirectly heated cathode 74, one on each side of the choke coil 75 to form with the choke coil 75 a filter circuit.

The switch 70, for example one of the toggle type, is utilized to open and close the circuit of the above described tuner unit and is shown in the open position. The selective energizer 23 comprises an operator arm 79 connected through a rectifier unit 80 to the wire 19 and carries a contact 81 adapted to make contact with the plate 82 connected to a contact engaged by the arm of the toggle switch 70 in the open position. The end of the switch arm 79 is provided with a projection 83 adapted to engage the end of the toggle switch arm 70. The rectifier unit 80 preferably comprises a bank of commercial type rectifiers as shown so that the unit is of ample capacity to cause a unilateral current of suitable value to be impressed on the residence lighting conductors for a purpose to be explained herein-after.

The amplifier and speaker unit connected to the residence lighting conductors 22-22 by means of wires 32 and 33 through condensers 30 and 31 to the primary 29 of the intermediate frequency coupling transformer as previously described when the switch 37 is in the closed position. An intermediate frequency amplifier tube 84 has its control grid 27 connected to one end of the secondary 28 of the intermediate frequency coupling transformer and its indirectly heated cathode 85 connected through a bias resistor 86 to the other end of the secondary 28, with a by-pass condenser 87 bridged across the resistor 86. The plate 88 of the amplifier 84 is connected to one end of the primary of an intermediate frequency transformer 89 and the other end of the primary of the intermediate

frequency transformer is connected to the wire 90 which is the positive common conductor of the plate supply. The screen grid 91 of the amplifier 84 is connected to an intermediate tap 5 of a voltage divider 92 by means of a wire 93.

A second detector vacuum tube 94 has its grid 95 connected through a grid condenser 96 bridged by a grid leak 97 to one end of the secondary of the intermediate frequency transformer 89. The indirectly heated cathode 98 is connected to the other end of the secondary of the transformer 89 and to the wire 99 which is the negative common conductor of the plate supply. The plate 100 of the detector tube 94 is connected to one end of the primary of an audio-frequency transformer 101. The other end of the primary of the transformer 101 is connected to the wire 90. A radio frequency by-pass condenser 102 is connected between the cathode 98 and the plate 100.

One end of the secondary of the audio-frequency transformer 101 is connected to the grid 103 of an audio-frequency amplifier tube 104. The other end of the secondary is connected to the wire 99 and through a bias resistor 105 to the indirectly heated cathode 106 of the amplifier tube 104. The bias resistor 105 is bridged by a by-pass condenser 107. The plate 108 of the amplifier tube 104 is connected to one terminal of the speaker 109. The other terminal of the speaker 109 is connected to the wire 90.

A transformer 110 supplies power to the amplifier-speaker unit and consists of a primary 111 connected across the supply wires 32 and 33. A secondary winding 112 in the power transformer 110 supplies current to the heater elements of the vacuum tubes 84, 94 and 104. An intermediate tap of the secondary winding 112 is connected to the wire 99. The wire 90 is connected through a choke coil 113 to an intermediate tap of a second secondary 114 in the power transformer 110. The secondary 114 is connected across the cathode 115 of a full-wave rectifier tube to supply energy for heating the cathode. Condensers 116 and 117 are bridged across from the wire 99 to either side of the choke coil 113 to form with the latter a filter circuit. Each end of a third secondary winding 118 of the power transformer 110 is connected to an anode 119 of the full-wave rectifying tube. An intermediate tap on the secondary 118 is connected to the wire 99 which completes the plate voltage supply circuit. The voltage divider 92 is connected across the wires 90 and 99.

The selective energizer 36 is connected to the residence lighting conductors by a wire 120 through a filter circuit consisting of choke coils 121 and 122 and condensers 123 and 124, and a wire 125 connected to the other residence lighting conductor 22. The wire 125 is also connected to a contact 126 of the switch 37 which cooperates with a contact 127 connected to the wire 33 to close the supply circuit of the amplifier-speaker unit. The above described filter circuit supplies current to the coil 128 of a relay which has a fixed contact 129 and a movable contact 130 adapted to be closed when the coil 128 is energized. The contacts 129 and 130 complete another relay circuit through a battery 131 and a relay coil 132. The relay coil 132 is adapted to operate the armature 133 of a ratchet relay having a shaft 134 provided with a disc 135 having a segmented periphery to provide a plurality of contacts 127, the spaces between which are filled 75 with insulating material to provide with the contacts

127 alternate open and closed circuit positions for the contact 126.

Operation of typical radio receivers incorporating principles of the present invention can be readily understood from the operation of the receiver diagrammatically shown in Fig. 2. The radio currents picked up by the aerial 11 are supplied to the tuner unit, tuned by the coupling transformer 38 and the variable condenser 41 and supplied to the first detector vacuum tube 40 through the control grid 39. A tuned circuit consisting of the secondary of the transformer 52, variable condenser 57, grid leak 58, grid condenser 54 and the tube 50 comprises an oscillator. The frequency of the current supplied by the oscillator transformer 52 differs from that in the antenna coupling transformer 38 by the frequency to which the intermediate frequency transformer 49 is tuned. This current is supplied by the oscillator transformer 52 to the first detector tube 40 through the cathode circuit thereof to be combined with the incoming radio currents to raise the wave length of the latter in accordance with the principles of the superheterodyne reception. The resulting radio current is supplied at the intermediate frequency amplifier tube 62 through the intermediate frequency transformer 49 and transferred to the output wires 18 and 19 through the intermediate frequency coupling transformer 14-15 and the condensers 16 and 17. The ratio of turns in the coupling transformer is preferably about one hundred to one and the condenser 16 is connected to the secondary 15 through a volume control 69. With the use of the intermediate frequency coupling transformer 14-15 and condensers 16 and 17, the tuner unit is low impedance coupled to the residence lighting conductors 22-22.

The selective energizer shown at 23 in Fig. 2 is adapted to impose a direct current impulse upon the residence lighting conductors 22-22 and is combined with the tuner circuit supply switch 70 so that the direct current impulse may be generated during the time the tuner circuit switch is being turned on. With the tuner circuit switch 70, preferably of the toggle type, in the off position as shown in full lines, when the operator arm 79 is rotated counter clockwise contact is made between contact 81 and contact 82 allowing current to flow from the wire 19 through the rectifier bank 80, operator arm 79, contacts 81 and 82, and the switch arm 70 to the wire 18. The period of flow of direct current will be for a relatively short time since as the operator arm 79 is further rotated the toggle switch 70 is swung over to break this direct current generating circuit and close the tuner supply circuit.

When the amplifier speaker unit switch 37 is closed the intermediate frequency current passes through conductors 32 and 33 which are low impedance coupled to the amplifier unit through condensers 31 and 32 and the intermediate frequency step up coupling transformer 29-28. The intermediate frequency current is supplied to the intermediate frequency amplifier tube 84 through its grid 27 from the secondary 28 and therein amplified. The amplified current is supplied from the plate circuit of the amplifier tube 84 through the intermediate frequency coupling transformer 89 to the grid 95 of the second detector tube 94. The resultant detected radio current is then supplied from the plate circuit of the detector tube 94 to the audio-frequency transformer 101 and the audio-frequency ampli-

fier tube 104 to be translated into sound by the speaker 109.

The switch 37 for the amplifier-speaker unit is operated by the direct current impulse imposed upon the alternating current of the residence lighting conductors 22-22 through operation of the selective responder control unit 36 in which the filter circuit chokes out the alternating current, allowing the direct current impulse to build up a magnetic field about the relay coil 128 sufficient to close the contacts 129 and 130 to cause the relay 132 to be energized from the battery 131. The resultant magnetic field about relay 132 causes the armature 133 to rotate the ratchet one notch causing the contact 126 to make contact with a contact segment 127 thereby closing the amplifying supply circuit. The switch 37 is turned off in a similar manner by the next direct current impulse superposed on the alternating current of the residence lighting conductors 22 when the operator arm 79 of the selective energizer 23 is rotated in a clockwise direction to turn the tuner switch 70 to an off position. A thyratronic may be used in lieu of the relay 128, 129, 130 for closing the ratchet relay circuit.

The present invention also contemplates the use of an oscillatory current method of turning the amplifier switch on and off from a remotely located energizer as well as by the direct current impulse method outlined above. Briefly this method comprises the use of means for superposing on alternating current or direct current of the residence lighting conductors a current of different frequency which will operate a switch operating device.

In Fig. 3 the circuit of the oscillator is depicted coupled to supply wires 18 and 19 through the tuner switch depicted and previously described. An oscillator tube 136 has its filament 137 supplied with current through the wires 138-138' and 139 connected respectively to supply wires 18 and 19. A ballast resistor 140 in series with the filament 137 and the wires 138 and 139 complete the filament circuit. The plate 141 of the oscillator tube 136 is connected through a coil 142 of a transformer to the wire 138. The grid 143 of the oscillator tube 136 is connected through a grid condenser 144 and a coil 145 of the transformer to the wire 138. A grid leak 146 is connected between the grid 143 and the wire 138 and a variable condenser 147 is bridged across the grid coil 145. The resultant oscillator circuit is coupled to the supply wires 18 and 19 through a coupling coil 148 and condensers 149 and 150. This oscillator circuit is tuned to superpose upon the residence lighting conductors 22-22 an alternating current of a frequency different from that of the current of the residence lighting conductors when the tuner switch is operated. This requirement is to be satisfied whether the current in the residence lighting conductors is alternating or direct, in the latter case the frequency being zero.

In Fig. 4 is shown a buzzer coil method of superposing an oscillatory control current upon the current of residence lighting conductors 22-22. A wire 151 connected to supply wire 138' and a wire 152 connected to supply wire 19 cooperate with a fixed buzzer contact 153 and an armature contact 154 to energize the buzzer coil 155. A coupling condenser 156 and a coil 157 of a transformer are connected in series across the armature contact 154 and the fixed contact 153. The coupling coil 157 cooperates with condensers 149 and 150 as in Fig. 3 to impress oscillatory control

currents upon the current of the residence lighting conductors 22-22 when the tuner switch is operated.

In Fig. 5 is shown the circuit of a selective responder unit adapted remotely to operate an amplifier switch with selective energizers of the types depicted in Figs. 3 and 4. Between the wires 120 and 125 is connected a bridged circuit having input terminals 158 and 159 and output terminals 160 and 161. Preferably, between the input terminal 159 and the output terminals 160 and 161 are connected respectively resistances 162 and 163, and between the input terminal 158 and output terminal 160 is connected a condenser 164 and between the input terminal 158 and output terminal 161 is connected an inductance 165. This bridge circuit is balanced so that at the frequency of the normal alternating current of the residence lighting conductors there is no potential difference between the output terminals 160 and 161. Thus oscillatory currents of different, for example, higher frequency in the residence lighting conductors supplied thereto by selective energizers of the types depicted in Figs. 3 and 4 will cause a potential difference to be formed between the output terminals 160 and 161 due to the fact that inductive reactance and capacitive reactance vary inversely when the frequency is varied. This condition will cause a current to flow through the relay coil 128 to close the circuit of the switch operating ratchet relay.

Obviously different arrangements of the resistances 162 and 163, condenser 164, and inductance 165 can be made to obtain similar results in accordance with the present invention. For example, the resistance 162 and the inductance 165 can be substituted for each other in the bridge circuit and by using variable resistances the bridge can be readily balanced so that there is no potential difference between the output terminals 160 and 161 at the frequency of the normal current in the residence lighting conductors. However, the arrangement shown in Fig. 5 is preferred since a maximum current flow through the relay coil 128 can thus be obtained.

In Fig. 6 is shown the circuit of another type of selective responder to be used with selective energizers of the types depicted in Figs. 3 and 4. The supply wires 120 and 125 are coupled through condensers 166 and 167 and the transformer 168 to a rectifier bridge circuit having input terminals 169 and 170 and output terminals 171 and 172. Across the input terminals 169 and 170 is connected a variable condenser 173. This rectifier bridge circuit is of the well known type having rectifier units 174, 175, 176 and 177 connected into the receptive arms thereof. The circuit is tuned to the frequency of the control currents supplied by the selective energizer 23 so that the bridge circuit will supply current to the relay coil 128 only when the control current is superposed on the residence lighting conductors 22-22.

In Fig. 7 is depicted the circuit of another type of selective energizer adapted to be used with the direct current method. An inductance coil 178 is connected across the supply wires 120 and 125 and is provided with an iron core 179 which is saturated with magnetic flux at the frequency of the normal alternating current of the residence lighting conductors so that any additional current such as a direct current component will cause a large increase of current to flow, due to over-saturation in core 179. This increase in current flowing through the relay coil 128 is sufficient to close the circuit of the ratchet relay.

It will thus be seen that the present invention efficiently attains the objects set forth above and provides means for utilizing the residence lighting conductors for transferring radio frequency currents from tuner units to remotely located amplifier and associated speaker units and for operating amplifier circuit switches from remotely located tuner switches.

Since certain changes may be made in the above construction and different embodiments of the invention could be made without departing from the scope, for example, in the direct current method of controlling a remotely located electrical device such as a switch, a continuous control current may be used in lieu of an impulse, it is intended that all matter contained in the above description or shown in the accompanying drawings shall be interpreted as illustrative and not in a limiting sense.

Having described our invention, what we claim as new and desire to secure by Letters Patent, is:

1. In a device for the remote control of an amplifier and associated speaker unit of a radio receiver, the combination with residence lighting conductors, a tuner unit, low impedance coupling connecting said tuner unit to the residence lighting conductors, an amplifier and associated speaker unit, low impedance coupling connecting said amplifier and associated speaker unit to the residence lighting conductors, of a switch between one side of the circuit of said amplifier and speaker unit and one of said residence lighting conductors, a selective responder unit connected to the residence lighting conductors and associated with said switch mechanically to operate the same, and a selective energizer connected to the residence lighting conductors remote from said selective responder unit for supplying a control current to said residence lighting conductors to be carried thereby to said selective responder unit for initiating operation thereof.

2. In a device for the remote control of an amplifier and associated speaker unit of a radio receiver, the combination with residence lighting conductors, a tuner unit, low impedance coupling connecting said tuner unit to the residence lighting conductors, an amplifier and associated speaker unit, low impedance coupling connecting said amplifier and associated speaker unit to the residence lighting conductors, of a switch in said amplifier and speaker unit between one side of the circuit of said amplifier and speaker unit and one of said residence lighting conductors, a selective responder unit in said amplifier and speaker unit connected to the residence lighting conductors and associated with said switch mechanically to operate the same, and a selective energizer in said tuner unit connected to the residence lighting conductors for supplying a control current to said residence lighting conductors to be carried thereby to said selective responder unit for initiating operation thereof.

3. A remote control device for operating a circuit switch comprising the combination with residence lighting conductors carrying alternating current and a switch between one side of the circuit of an electrical device and one of said residence lighting conductors, of a selective energizer comprising means located remotely from said electrical device and connected to the residence lighting conductors to superpose a direct control current upon the alternating current in the latter, and a selective responder unit connected to the residence lighting conductors and

associated with said switch mechanically to operate the same, said unit being adapted to respond to the direct control current superposed on the alternating current of the residence lighting conductors.

5

4. In a device for the remote control of an amplifier and associated speaker unit of a radio receiver, the combination with residence lighting conductors carrying alternating current of a selective energizer connected to the residence lighting conductors comprising means to superpose a direct control current upon the alternating current in the latter, a switch between one of said residence lighting conductors and one side of the circuit of said amplifier and associated speaker unit located remotely from said energizer, and a selective responder unit associated with said switch comprising means mechanically to operate said switch and means connected to the residence lighting conductors responsive to the direct control current to initiate operation of said switch operating means.

10

5. A remote control device for operating a circuit switch comprising the combination with residence lighting conductors carrying alternating current and a switch between one side of the circuit of an electrical device and one of said residence lighting conductors, of a selective energizer comprising means located remotely from said electrical device and connected to the residence lighting conductors to superpose a direct control current upon the alternating current in the latter, and a selective responder unit associated with said switch comprising means mechanically to operate the switch and means responsive to the direct control current superposed upon the alternating current of the residence lighting conductors connected to the latter adapted to initiate operation of said switch operating means.

15

6. In a device for the remote control of an amplifier and associated speaker unit of a radio receiver, the combination with residence lighting conductors carrying alternating current and a tuner circuit switch, of means connected to said residence lighting conductors and physically associated with the tuner circuit switch to be operated mechanically by the action necessary to close said switch to superpose a direct control current upon the alternating current of the residence lighting conductors, a switch between one side of the circuit of said amplifier and associated speaker unit and one of said residence lighting conductors, means mechanically to operate the latter switch, and means connected to said residence lighting conductors responsive to the direct control current superposed on the alternating current of the residence lighting conductors adapted to initiate operation of said switch operating means.

20

7. In a device for the remote control of an amplifier and associated speaker unit of a radio receiver, the combination with residence lighting conductors carrying alternating current, a tuner circuit switch connected to the residence lighting conductors and an amplifier switch connected to the residence lighting conductors, of rectifying means physically associated with the tuner circuit switch connected across the residence lighting conductors by the action necessary to close said tuner circuit switch to superpose a direct control current upon the alternating current of the residence lighting conductors, means to operate the amplifier circuit switch, and means responsive to the direct control current superposed on the alternating current of the residence

lighting conductors adapted to initiate operation of the amplifier switch operating means.

8. In a device for the remote control of an amplifier and associated speaker unit of a radio receiver, the combination with residence lighting conductors carrying alternating current, a tuner circuit switch connected to the residence lighting conductors and an amplifier switch connected to the residence lighting conductors, of rectifying means physically associated with the tuner circuit switch connected across the residence lighting conductors by the action necessary to close said tuner circuit switch to superpose a direct control current upon the alternating current of residence lighting conductors, means to operate the amplifier circuit switch, a filter circuit connected to the residence lighting conductors adapted to choke out the alternating current component while passing the direct current component, and means responsive to the direct control current connected to said filter circuit adapted to initiate operation of said amplifier switch operating means.

9. In a device for the remote control of an amplifier and associated speaker unit of a radio receiver, the combination with residence lighting conductors carrying current, a tuner unit low impedance coupled to the residence lighting conductors, an amplifier unit low impedance coupled to the lighting conductors, a switch in the power supply circuit of said tuner unit, a switch in the power supply circuit of said amplifier unit, of a selective energizer associated with said tuner switch and comprising means connected across the residence lighting conductors by the action necessary to close said tuner circuit switch to superpose on the current in the latter a control current, and a selective responder unit physically associated with said amplifier switch mechanically to operate the latter and connected to the residence lighting conductors to be operated by the superposed control current.

10. In a device for the remote control of an amplifier and associated speaker unit of a radio receiver, the combination with residence lighting conductors carrying alternating current, a tuner unit low impedance coupled to the residence lighting conductors, an amplifier unit low impedance coupled to the residence lighting conductors, a switch in the power supply circuit of said tuner unit, a switch in the power supply circuit of said amplifier unit, of a rectifier unit physically associated with the tuner circuit switch connected across the residence lighting conductors by the action necessary to close said tuner circuit switch to superpose a direct control current upon the alternating current of the residence lighting conductors, means to operate said amplifier circuit switch, a filter circuit connected to the residence lighting conductors adapted to deliver the direct control current, and means connected to said filter circuit adapted to respond to the direct control current and initiate operation of said amplifier circuit switch operating means.

11. In a remote control device the combination with conductors carrying alternating current of normal commercial frequencies of a selective energizer adapted to superpose on the alternating current of the conductors an oscillatory control current, and a selective responder adapted to respond to the oscillatory control current, said selective responder comprising a bridge circuit

having four arms, a pair of input terminals and a pair of output terminals with a resistance unit in each of two of the arms connected between an input terminal and an output terminal, a capacity unit connected between an input terminal and an output terminal in the third arm and an inductance connected between an input terminal and an output terminal in the fourth arm, said bridge circuit being balanced so that the output terminals are at the same potential at the frequency of the normal alternating current of the conductors.

12. In a remote control device the combination with conductors carrying alternating current of normal commercial frequencies, of a selective energizer adapted to superpose on the alternating current of the conductors an oscillatory current of different frequency, a selective responder comprising a bridge circuit having input terminals connected to the conductors and output terminals adapted to supply control current, equal resistance units connected between one input terminal and the two output terminals, a capacity unit connected between the other input terminal and an output terminal and an inductance connected between the latter input terminal and the other output terminal, said bridge circuit being balanced so that the output terminals are at the same potential at the frequency of the normal current of the conductors.

13. In a device for the remote control of an amplifier and associated speaker unit of a radio receiver, the combination with residence lighting conductors carrying alternating current and a remote tuner unit of a selective energizer at the tuner unit connected to the residence lighting conductors to superpose on the alternating current thereof an alternating current of higher frequency, a switch to open and close the amplifier circuit, and a selective responder having means to operate said switch, said selective responder comprising a bridge circuit having input terminals connected to the conductors and output terminals adapted to supply control current to the switch operating means, equal resistance units connected between one input terminal and the output terminals, a capacity unit connected between the other input terminal and an output terminal and an inductance connected between the latter input terminal and the other output terminal, said bridge circuit being balanced so that the output terminals are at the same potential at the frequency of the normal alternating current of the conductors.

14. In a remote control device the combination with residence lighting conductors carrying alternating current of normal commercial frequencies, of a selective energizer adapted to superpose on the alternating current of the conductors a direct current component, and a selective responder comprising an iron core inductance connected into a circuit across the residence lighting conductors, the core of which is saturated with magnetic flux at the normal frequency of the residence lighting conductors so that the direct current component will cause an over-saturation resulting in an increase in the current flow, said increase in the current flow being adapted to operate a control device.
